E. W. LANE,
ELECTRIC LIGHTING SYSTEM FOR AUTOMOBILES,
APPLICATION FILED JULY 26, 1915.

1,276,934.

Patented Aug. 27, 1918.

Inventor,
Ernest Wilson Lane, by
G. C. Kennedy,
Attorney.

UNITED STATES PATENT OFFICE.

ERNEST WILSON LANE, OF WAVERLY, IOWA.

ELECTRIC-LIGHTING SYSTEM FOR AUTOMOBILES.

1,276,934.

Specification of Letters Patent. Patented Aug. 27, 1918.

Application filed July 26, 1915. Serial No. 42,093.

To all whom it may concern:

Be it known that I, ERNEST WILSON LANE, a citizen of the United States of America, and a resident of Waverly, Bremer county, 5 Iowa, have invented certain new and useful Improvements in Electric-Lighting Systems for Automobiles, of which the following is a specification.

My invention relates to improvements in 10 electric lighting systems for automobiles, and the object of my improvement is to supply convenient means for switching lamps which are in series circuit with a magneto or other source of electric current into a 15 multiple circuit with a source of electric current of lower voltage, whereby the brilliancy of the lamps' illumination may be maintained at times when the usual source of power is incapacitated for action.

20 This object I have accomplished by the means which are hereinafter described and claimed, and which are illustrated in the accompanying diagram of my improved switch adapted to alternately place a plurality of lamps in a series circuit, or in multiple circuits with different sources of electric current.

It is well known that when lamps are in 30 series circuit with a magneto or other source of electric current, any failure of the magneto or other source of current will extinguish all the lamps in the series. This is peculiarly inconvenient where such a system of electric lighting is installed in a 35 motor-car, since in case the car is brought to a stop or the motor thereof is disabled by any cause, the magneto will likewise fail to supply current, thus extinguishing the lamps at times when their illumination is 40 necessary, to prevent collisions and traffic interference.

My lighting system is applicable for any installation desired, and various changes 45 may be made in the parts thereof, without departing from the scope of my invention or its principles of operation. Also, the respective values of the voltages of its different sources of electric current may vary, and are not confined to certain multiples or fixed 50 relations.

The diagram given is based upon a plurality or pair of six volt lamps 1 and 2 in series circuit with the 12 volt magneto 29. The switch comprises a boxing 3 containing 55 a face-plate 10 of insulation secured by screws 37. A pivot-pintle 4 is fixed cen-

trally in said plate and carries a rock-body 5 of insulation, the latter having a projecting arm 6 with terminal handle 7, both also of insulation. Embedded in the rock-body 60 5 and spaced apart, are a pair of like arc-shaped bars 8 and 9, of conducting material, with their convex sides adjacent to each other.

The bar 8 has the conducting terminals 65 24 and 25 at its opposite extremities. The bar 9 has the conducting terminals 27 and 26 at or near its opposite ends. The bar 9 has a contact 22 to contact with the terminal 17. The space between the contacts 16 and 17 being short, a ridge of insulation 23 is extended upward from the base 10 between them to prevent short-circuiting between them, when the contact part 22 is in conducting contact with the terminal 17 underneath.

The conducting terminals or posts 13, 14, 15, 16, 17, 18, 19, 20 and 21 are seated in the insulation 10, and conductors lead from them as hereinafter described.

80 The terminals 18 and 21 are in circuit with opposite poles of the magneto 29, by means of the conductors 31 and 30, respectively. The terminals 19 and 20 are in circuit with opposite poles of the battery 28 85 by means of the conductors 33 and 32 respectively.

The lamps 1 and 2 are in series circuit with the terminals 13 and 15 by means of the conductors 34 and 35, and intermediate 90 conductor 39. A conductor 36 leads from the middle of the conductor 39 to the terminal 14. A conducting bar 11 embedded in the insulation 10 leads from the terminal 13 to the terminal 17. A conducting bar 12 95 embedded in said insulation leads from the terminal 15 to the terminal 16.

The 6 volt lamps 1 and 2 are arranged as usual in series circuit with the 12 volt magneto 29. While being put into the series circuit the switch is rocked to the right to have the switch terminals 25 and 26 in contact with the terminals 21 and 18 respectively, and the switch terminals 24 and 27 in contact with the terminals 13 and 15 respectively.

When the switch is rocked to the left, the battery 28 is placed in multiple circuit with said lamps as follows: from the negative pole of said battery to its positive pole, 110 through the conductor 33, contacts 19 and 26, bar 9, contacts 27 and 16, bar 12, termi-

nal 15, conductor 35, lamp 2, conductors 39 and 36, contacts 14 and 24, bar 8, contacts 25 and 20, and the conductor 32. From said negative pole to its positive pole, by way of 5 the conductor 33, contacts 19 and 26, bar 9, contacts 22 and 17, bar 11, terminal 13, conductor 34, lamp 1, conductors 39 and 36, contacts 14 and 24, bar 8, contacts 25 and 20, and the conductor 32. In this way, each 10 lamp is provided with a 6 volt current, providing as effective illumination as by the 12 volt magneto in series circuit with both lamps.

The 6 volt battery is relatively inexpensive and of comparatively small weight and dimensions, hence it is usefully employed in such a multiple circuit, in cases of emergency.

Having described my invention, what I 15 claim as new, and desire to secure by Letters Patent, is:

In combination, translating devices, a source of electric current of relatively low voltage, a source of electric current of rela-

tively high voltage, a conductor connecting 25 said translating devices, conductors leading from said devices and each having a pair of terminals, a bridging conductor leading from the first-mentioned conductor to a terminal, conductors leading from the source 30 of low voltage current to terminals, other conductors leading from the source of high voltage current to terminals, and a multi-contact switch having separated sets of connected contacts operable selectively with 35 said translating-devices terminals and with said bridging conductor terminal to independently place said translating-devices in series circuit with said source of high voltage current or in parallel circuit with said 40 source of low voltage current.

Signed at Waterloo, Iowa, this 21st day of July, 1915.

ERNEST WILSON LANE.
